Application February 16, 1934, Serial No. 50,752

Term of patent 14 years

To all whom it may concern:

Be it known that I, CARL M. PLOCHMAN, a citizen of the United States, residing at Evanston, in the county of Cook and State of Illinois, have invented a new, original, and ornamental Design for a Bottle or the like, of which the following is a specification, reference being had to the accompanying drawing forming part hereof.

Fig. 1 is a front elevational view of a bottle or the like embodying my new design.

Fig. 2 is a side elevational view of said bottle or the like.

Fig. 3 is a top plan view of said bottle or the like.

I claim:

The ornamental design for a bottle or the like, substantially as shown.

CARL M. PLOCHMAN.
